UNITED STATES PATENT OFFICE.

THEODORE TAYLOR, OF CEDARVILLE, CALIFORNIA.

ELECTRIC RAILWAY-TRACK ALARM.

SPECIFICATION forming part of Letters Patent No. 401,472, dated April 16, 1889.

Application filed October 8, 1888. Serial No. 287,501. (No model.)

To all whom it may concern:

Be it known that I, THEODORE TAYLOR, of Cedarville, in the county of Modoc and State of California, have invented a new and Improved Electric Railway-Track Alarm, of which the following is a specification, reference being had to the annexed drawings, forming a part thereof, in which—

Figure 1 is a perspective view of my improved electric railway-track alarm, and Fig. 2 is a detail side elevation of one of the hooks for fastening the conductors to the rails.

Similar letters of reference indicate corresponding parts in both views.

The object of my invention is to provide a simple and efficient alarm for use in connection with railway-tracks for indicating when the track is broken or displaced.

My invention consists in the combination, with the railway-rails, of conductors connected with the rails by suitable fastenings insulated and arranged to form a complete electric circuit, including a battery and an alarm device, all as hereinafter more fully described.

To the track-rails A A' are attached the insulated conductors B B' by means of the hook-bolts C. (Shown in detail in Fig. 2.) The conductors B B' are made in sections, so that they may be easily applied to the rails, or removed therefrom when necessary, and each conductor is provided with an insulating coating, a, of rubber or other suitable insulating material. The conductors B B' are connected

together at a distant point, b. The conductor B is connected with one pole of a battery, D, by means of the wire c. The conductor B' is connected with the magnet d of the alarm apparatus by means of the wire e, and the said magnet d is in electrical communication with the remaining pole of the battery D.

The alarm apparatus consists of a drum, f, with a cord, g, wound around it and carrying a weight, h, a scape-wheel, i, pallets j, working in the scape-wheel, a bell-hammer, k, operated by the pallets and adapted to strike the bell l. Upon the shaft of the drum f is secured a ratchet-wheel, m, which is prevented from turning by the pawl n. The pawl n carries the armature o, and a spring, p, connected with the pawl n, tends to draw the said pawl out of engagement with the ratchet-wheel m. So long as the circuit of the conductors B B' is complete the electro-magnet d is energized, the armature o is drawn down, and the pawl n is kept in engagement with the ratchet m; but when the conductor B or B' is broken the armature o is released and the spring p pulls up the pawl n, allowing the weight h to fall and give the alarm through the action of the scape-wheel, pallets, and bell-hammer.

By means of my improvement any break in the rail will be instantly detected. Any means of generating an electric current may be employed, either battery or dynamo, as may be most convenient.

Having thus described my invention, I claim as new and desire to secure by Letters Patent—

The combination, with the railroad-rails A A', the alarm apparatus, and an electric generator, of the insulated electric conductor B B', extending alongside and between the rails, and the hooks C, which pass through said rails and secure the conductors to the side thereof, all as shown and described.

THEODORE TAYLOR.
